HINGE

Fred G. Bates, Highland Park, and Landlin B.
Bishop, Detroit, Mich.

Application February 16, 1934, Serial No. 711,458

9 Claims. (Cl. 16—166)

This invention relates to improvements in hinges, and refers particularly to concealed hinges.

It is an object of the invention to provide a simple, strong, and durable form of hinge wherein in the movable plate, which is intended for attachment to a door, is swung outwardly and forwardly from the stationary plate, which is intended to be mounted upon a doorpost or frame, when the hinge is opened so that the movable plate then rests materially in advance of the stationary plate; and wherein all the portions of the hinge are concealed, partly between the two plates and partly behind one of them, when the hinge is closed.

Another object of the invention is to provide a hinge consisting of two plates intended for attachment to a door and doorpost or frame respectively, one of the plates being apertured for the passage of a tongue extending from the other plate, and guide means for the tongue which project both forwardly and rearwardly from the apertured plate, so that the tongue passes through the aperture as the hinge is opened or closed and is guided throughout its movement.

A further object of the invention is to provide a hinge wherein a stop is provided to limit the angular movement of the two plates to one another.

Having thus briefly stated some of the objects and advantages of the invention, we will now proceed to describe a preferred embodiment thereof with the aid of the accompanying drawings, in which:

Figure 1 illustrates a plan view of the hinge when closed,

Figure 2 is a side view thereof.

Figure 3 shows a plan view of the hinge when fully open, and

Figure 4 is a side view thereof.

Figures 5 and 6 are views on the lines 5—5 and 6—6 respectively of Figure 3.

Figure 7 is a plan view of the hinge when partially open.

Referring to the drawings, 1 and 2 designate two vertical plates either one of which is intended for attachment to a doorpost or frame and the other to a door. Both the plates 1 and 2 are provided in the present instance with a plurality of openings 3 for the passage of screws—not shown—to secure these plates to the parts to be connected by the hinge.

The plate 1 is apertured at 4, usually substantially centrally of its height and preferably from 55 one of its vertical margins and for the greater

portion of its width. Extending both forwardly and rearwardly from the plate 1 are horizontal guides 5, the adjacent faces of which are flush with the upper and lower sides of the aperture 4. Formed through the guides 5 are vertically aligned slots 6 which extend across and on both sides of the plate 1, and integral with the latter adjacent its vertical margin through which the aperture 4 does not extend are a plurality of spaced and vertically aligned knuckles 7. The latter are positioned forwardly relative to the plate 1, and one of the said knuckles is located in the same horizontal plane as at least a portion of the aperture 4.

Extending through the knuckle 7 is a pin 8 on 15 which one extremity of each of two links 9 are pivotally mounted. These links are arranged one above the other on opposite sides of the central knuckle 7. Formed integral with the plate 2 are other vertically spaced knuckles 10, which, 20 when the hinge is closed, extend towards the plate 1 and towards the side thereof remote from the knuckles 7. A second pin 11 passes both through the knuckles 10 and the opposite extremities of the links 9.

A tongue 12, which projects horizontally from the plate 2 and is slidable between the guides 5, has a guide pin 13 extending vertically through its outer extremity which travels in the slots 6. In order to insure clearance for the extremities of the guide pin 13 recesses 14 may be formed through those portions of the plate 1 contiguous to the outer sides of the slots 6. The tongue 12, which is preferably so formed at 12a as to contact the central knuckle 7 when the hinge is fully open and thus form a stop, may either be integral with the plate 2, or secured thereto as by a screw 15 shown in Figures 3 and 5.

As the hinge is opened, assuming that the plate 1 remains stationary, the rear portions 6a of the slots 6 cause the plate 2 to turn sufficiently for a door—not shown—secured to the said plate 2 to swing clear of the door frame. The inclination of the plates 1 and 2 to one another when the hinge is thus partly open may be clearly seen from Figure 7. As the hinge continues to open the guide pin 13 travels towards the front extremities of the slots 6 along a more nearly straight path. During this portion of the movement the plate 2 swings forwardly relative to the plate 1 until the stop portion 12a of the tongue 12 contacts the central knuckle 7. Meanwhile the movement of the plate 2 has also been controlled, and the plate itself supported by, the links 9. It will further be noted that by providing

the knuckles 7 and 10 on opposite sides of the plates 1 and 2 and by making the links substantially S-shaped as shown, that when the hinge is closed the two said plates rest parallel, and in close proximity, to one another. The rear portions of the guides 5 may also be strengthened by a vertical connecting wall 5a.

While in the foregoing the preferred construction of the hinge has been described and shown, it is understood that alterations and modifications may be made thereto so long as they fall within the scope of the appended claims.

What we claim is:

1. A hinge consisting of two flat plates which, when the hinge is closed, rest in proximity and substantially parallel to one another, connecting means extending substantially diagonally between the two plates when the hinge is closed, said connecting means being pivoted at each extremity to one of the plates, the two pivot axes being parallel, a tongue integral with one plate projecting laterally therefrom, guide means integral with the other plate and extending laterally therefrom, and cooperating means carried by the tongue and guide means for controlling the path of movement of one plate relative to the other.

2. A hinge consisting of two flat plates one of which is apertured, a tongue integral with and extending laterally from the other plate and being slidable through said aperture, guide means integral with and extending laterally from the apertured plate, means carried by the outer extremity of the tongue slidable in the guide means, and connecting means pivoted at each extremity to one of the plates and positioned between the adjacent faces of the plate when the hinge is closed.

3. A hinge consisting of two plates one of which is apertured, a tongue extending from the other plate and being slidable through said aperture, guide means extending laterally from both sides of the apertured plate and through the aperture, means carried by the outer extremity of the tongue slidable in the guide means, and connecting means for the plates pivoted at each extremity to one of the latter about parallel axes.

4. A hinge consisting of two flat plates one of which is apertured, a tongue integral with and extending laterally from the other plate slidable through said aperture, guide means for the outer extremity of the tongue integral with and extending laterally from the apertured plate, and connecting means pivoted at each extremity to one of the plates and positioned between the plates when the hinge is closed, said tongue being so formed that a portion thereof contacts a portion of the apertured plate to limit the opening of the hinge.

5. A hinge consisting of two plates which lie substantially parallel and in proximity to one another when the hinge is closed, a tongue integral with and extending laterally from one plate, guide means integral with and extending laterally from the other plate, a projection extending from the tongue slidable in the guide means, said tongue being so formed that a portion thereof contacts a portion of the other plate to limit the maximum angularity of the plates to one another, and connecting means between the plates pivoted at each extremity to one of the latter, said connecting means being substantially diagonally dis-

posed between the plates when the hinge is closed.

6. A hinge consisting of two plates which lie substantially parallel and in proximity to one another when the hinge is closed, one of the plates being apertured, a tongue extending from the other plate and being slidable through the aperture, slotted guides extending laterally from both sides of the apertured plate and through the aperture, a projection carried by the outer extremity of the tongue slidable in the slots and through the aperture, and connecting means pivoted at each extremity to one of the plates and extending substantially diagonally between the latter when the hinge is closed.

7. A hinge comprising two plates which are substantially parallel and in proximity to one another when the hinge is closed, spaced knuckles integral with each plate, the two sets of knuckles being positioned adjacent diagonally opposite margins of the plates when the hinge is closed, links pivoted at each extremity to one set of knuckles and disposed between the plates, one of the plates being apertured, a tongue rigidly mounted on the other plate and projecting therefrom, said tongue extending through the aperture, guides extending both forwardly and rearwardly from the apertured plate, said guides having aligned slots formed therethrough which extend across and on both sides of the apertured plate, a projection extending from the outer extremity of the tongue slidable in the slots, and the latter being so formed that as the plates move apart the other plate is moved forwardly from the apertured plate as the inclination of the two plates to one another increases.

8. A hinge comprising two plates which are substantially parallel across their faces and in proximity to one another when the hinge is closed, spaced knuckles integral with each plate, the two sets of knuckles being positioned adjacent diagonally opposite margins of the plates when the hinge is closed, links pivoted at each extremity to one set of knuckles and disposed between the plates, a tongue projecting from one of the plates, and guide means for the outer extremity of the tongue to control the path of movement of the first named plate, said guide means extending across and on both sides of the other plate, and supported by the latter.

9. A hinge comprising two plates which are substantially parallel across their faces and in proximity to one another when the hinge is closed, spaced knuckles integral with each plate, the two sets of knuckles being positioned adjacent diagonally opposite margins of the plates when the hinge is closed, links pivoted at each extremity to one set of knuckles and disposed between the plates, one of the plates being apertured, a tongue extending from the other plate and through the aperture, guides extending from the apertured plate to receive the outer extremity of the tongue and control the path of movement of the other plate, a portion at least of the tongue being in alignment with one of the eyes on the first named plate, and said tongue being so formed that a portion thereof contacts the knuckle in alignment with it to limit the maximum inclination of the plates to one another.
